In France January 5, 1934

Term of patent 14 years

To all whom it may concern:

Be it known that I, Louis Marie Paul Charles Vernin, a citizen of the Republic of France, residing at Melun (Seine-et-Marne), have invented a new, original, and ornamental Design for a Multicellular Receptacle, of which the following is a specification, reference being had to the accompanying drawing, forming part thereof.

Figure 1 is a perspective top plan view;

Figure 2 is a perspective view in elevation; and
Figure 3 is a bottom plan view.

I claim:

The ornamental design for a multicellular receptacle as shown.

In testimony whereof I have signed this specification.

LOUIS MARIE PAUL CHARLES VERNIN.
